UNITED STATES PATENT OFFICE

118,441

DESIGN FOR A HEAD COVERING

Solomon E. Rains, New York, N. Y.

Application January 28, 1938, Serial No. 74,623

Term of patent 3½ years

To all whom it may concern:

Be it known that I, Solomon E. Rains, a citizen of the United States, residing at Manhattan, in the county of New York and State of New York, have invented a new, original, and ornamental Design for a Head Covering, of which the following is a specification, reference being had to the accompanying drawing, forming part thereof.

Fig. 1 is a side view of the head covering of my invention showing the design as worn; and

Fig. 2 is a drawing of the same head covering folded for display preparatory to application to wearer's head.

I claim:

The ornamental design for a head covering, as shown and described.

SOLOMON E. RAINS.
